UNITED STATES PATENT OFFICE.

LENA H. WHITE, OF CHICAGO, ILLINOIS.

WINDOW-CURTAIN APPLIANCE.

No. 879,226.

Specification of Letters Patent.

Patented Feb. 18, 1908.

Application filed October 16, 1905. Serial No. 282,935.

To all whom it may concern:

Be it known that I, LEONA HERZOG WHITE, a citizen of the United States, residing at Chicago, in the county of Cook and State of Illinois, have invented certain new and useful Improvements in Window-Curtain Appliances, of which the following is a specification.

This invention relates to means for facilitating the insertion of lace-curtain rods and the like into the hem, plait or fold which engages the rod. As is well known, housewives and others upon whom devolve the duty of mounting curtains have usually more or less difficulty in guiding the rod through the loop of the curtain, or the fold provided for the rod, by reason of the blunt end of the rod being arrested by the filaments or threads, and the object of my invention is to overcome this difficulty by providing a removable threading-point, or tapered end, which may be conveniently and rapidly adjusted upon the end of the rod and made to serve as a temporary guide for the latter during its passage through the fold and the web thereof. And with the foregoing named object in view my invention consists in the novel threading-point hereinafter described in detail, illustrated in the drawing and defined in the claims, and in its combination with a curtain-rod.

In the drawing—Figures 1 to 4 inclusive illustrate four forms of the invention, Figs. 1 to 3 being outside views and Fig. 4 a longitudinal section. Figs. 5, 6 and 7, are transverse sections of, respectively, Figs. 1, 2 and 3. Fig. 8 is a view of the open end of the point shown in Fig. 4. Fig. 9 is a perspective view showing a fragment of curtain and the pointed end of a rod partly inserted in the fold or hem of the curtain.

Referring to the drawings in detail, 2 and 3 represent two different sizes of hollow or tubular curtain-rods, while 4 represents a solid rod.

5, 6 and 7 represent three different forms of tips or points adapted to be mounted upon the ends of either hollow or tubular rods and 8 represents a form of tip or point adapted for tubular rods. The body of the threading-point is in the form of a sheet-metal cone provided with a series of spring-jaws or clamps 9 which may be separated to admit between them the rod 2. The dotted lines show the depth of insertion of the latter and also indicate how rods of varying sizes may be served

by the same point. If the rod is of small diameter it will enter deeper into the cone, or closer to its apex, than if it is large, the maximum diameter of the rod being limited to the internal diameter of the base of the cone. The spring-jaws 9 may be integral with the conical portion, or be separate members secured to the cone. In the latter event they would either be attached to the inner walls of the base of the cone or to the edges so as to present no projection liable to catch the threads or weave of the curtain-loop, fold or hem 10 of the curtain 11. After the point has been started through the passage 12 of the fold 10 the latter will be expanded usually some distance ahead of the apex 13 clearing a path through the fold for the extreme end of the point and for this reason the apex 13 should not be too far removed from the base 14; that is the taper of the cone should be as short as possible without making the inclination of the outer surface of the cone too abrupt for easy sliding contact with the sides of the opening 12.

The threading point shown in Fig. 2 is made of a single piece of spring sheet-metal cut and rolled into a form which provides the conical tip labeled 6 and the cylindrical portion 15 the meeting edges of which are cut away slantingly at 16 and overlap as indicated by dotted lines at 17. In its normal position the cylindrical portion as well as the conical portion have the form substantially of the point shown in Fig. 3, which is identical with Fig. 2 except that the cylindrical portion is not cut away as at 16. Fig. 2, therefore, is substantially the point 6 expanded upon the large rod 3 instead of the small rod 4. In Fig. 3 the meeting edges 16 and 17 of the part 15 overlap considerably, as shown plainly in cross section view, Fig. 7. These edges extend to the apex of the conical portion where an overlapping also exists, though the expanding movement is smaller in the conical than in the clamp or jaw-portion 15 or 15'.

In Fig. 4 I have shown a cone-point 8 provided with internal-engagement means suitable for rods such as 2 and 3, consisting of a bent spring formed into a pair of friction-arms 18 and 19 arranged to be normally expanded apart as indicated by dotted lines instead of normally contracted as their equivalent parts in Figs. 2 and 3. The spring 18—19 is soldered, or otherwise suitably secured, at 20, 20 and any suitable num-

ber, other than merely two, of arms 18 and 19 may be provided.

In Fig. 1 the conical portion or head need not be split as in Figs. 2 and 3. The same is true of Fig. 4, but in all of the forms shown the threading point is adapted for rods of a large variety of sizes, which sizes may range from, say, one-eighth of an inch to the usual three-eighths size, or even larger, according to the normally contracted or expanded position of the resilient, or body, portion of the threading-point.

What I claim as new and desire to secure by Letters Patent is—

- 15 1. A tapered threading-point provided with an expandable body constructed to cover the end of a curtain rod and to be held there-upon by yielding frictional engagement.
- 20 2. A tapered threading-point adapted to cover the end of a curtain rod and provided with a clamping device for fastening said point removably to said rod.
- 25 3. The combination, with a curtain-rod, of a device which comprises a threading-point an enlarged body-portion adapted to expand the hem of a curtain after said threading-point has served to make the initial opening in the hem, and elastic means for fastening said head against the end of said rod.
- 30 4. The combination with a curtain-rod of a threading point which comprises a substantially conical head having a base of larger circumference than the circumference of said rod and having a flexible and expandable body portion the circumference of which is normally less than the circumference of said rod.
- 35 40 5. A threading-point for curtain-rods that consists of a substantially conical head pro-

vided with an elastic and expandible body portion adapted to confine said head upon the ends of rods of different cross-sections.

6. A threading-point for curtain-rods which consists of a substantially conical point provided with contractile and expandible jaws or arms adapted to be clamped upon the end of a curtain-rod so as to hold said point against the end of said rod and to cover said end.

7. A threading-point for curtain-rods consisting of a single metallic body having a tapered or conical forward end and a rear contractile and expandible portion adapted to pass the ends of rods of varying diameters and to be held upon the latter by frictional contact.

8. A threading-point comprising a hollow cone and an elastic clamping portion, the inner walls, from apex to base, of said cone adapted to bear against the end-edges of any one of a variety of curtain-rods whose cross-sections equal any one of the interior cross-sections of said cone, said clamping portion arranged to yieldingly engage the sides of the rod and hold said cone in position against said end.

9. A threading-point comprising a single sheet of spring metal which has been rolled into an expandible and substantially cylindrical body having a conical tip, the meeting edges of said body being normally overlapped, for the purpose set forth.

In testimony whereof I have hereunto set my hand in the presence of two subscribing witnesses.

LENA H. WHITE.
